UNITED STATES PATENT OFFICE.

JOHN B. WARING, OF NEW YORK, N. Y., ASSIGNOR TO THE AMERICAN DIAMOND ROCK BORING COMPANY, OF SAME PLACE.

POWER ROCK-DRILL.

SPECIFICATION forming part of Letters Patent No. 271,168, dated January, 23 1883.

Application filed July 1, 1882. (No model.)

To all whom it may concern:

Be it known that I, JOHN B. WARING, of New York, in the county and State of New York, have invented a certain new and useful Improvement in Power Rock-Drills, of which the following is a specification.

The nature of my improvement is fully described with reference to the accompanying drawings, and set forth in the claims.

In the accompanying drawings, Figure 1 is a sectional elevation of a drilling apparatus. Fig. 2 is a sectional view of the same, taken in a plane at right angles to Fig. 1. Fig. 3 is a section, on a larger scale, of the motor, whereby by the thrust of the drill-rod is produced. Fig. 4 is a longitudinal section of a modified form of column for the frame of the apparatus. Fig. 5 is a sectional view of one of the devices for supporting on the columns of the frame the drill-rod, the motor whereby its thrust is produced, and appurtenances. Fig. 6 is a view of such device, taken in a plane at right angles to that of Fig. 5, and Fig. 7 is a section of a valve controlling the motor, whereby the thrust of the drill-rod is effected.

Similar letters of reference designate corresponding parts in all the figures.

I will begin my description of the apparatus with an explanation of its frame. Although I prefer to use this frame, it is not essential to my present improvement, and I do not intend to claim it here.

A designates two columns, and B B' head-pieces or yokes connected with them by pins 35 a. The head-piece or yoke B' has secured to it by a pin, b, a swivel-bearing, C, which is connected by a pin, c, with a foot-piece, C'. The upper head-piece or yoke, B, is provided with a screw, D, which may be turned by a bar inserted in holes d in its head. The column A may be made in sections, united by thimbles E, if desired, as shown in Fig. 4.

I will now turn to the drill-spindle and the motor, whereby its thrust is effected.

F designates the drill-spindle, and G designates the cylinder, of the motor referred to. The piston H of the motor is secured to the inner end of the drill-spindle. The cylinder G of this motor is secured to a frame, I, and the 50 drill-rod passes through such frame. This frame I is provided with trunnions e, which fit in

bearings f in devices which are provided with slide-pieces g, that fit the columns A of the main frame. In the slide-pieces g are plates h, which may, by means of screws i, be forced against the columns A, so as to clamp the slide-pieces thereon. It will be readily understood that the drill-rod and motor may, by means of these slide-pieces, be adjusted up or down on the columns of the main frame and secured in different positions; also, that they may be adjusted at different angles relatively to said columns, owing to their support by the trunnions e in the bearings f. These adjustments, together with the adjustment which may be had by turning the main frame and the provisions for securing the drill-rod and motor on the main frame in different positions, enables the drill to be made to operate at any desired part of a tunnel or shaft. The cylinder G of the motor has affixed to its outer end a cap, G', with which communicates a pipe, K. At the lower end it has affixed to it an externally-screw-threaded coupling-piece, G², which screws into one end of the frame I.

L is a bevel-gear wheel, which has an opening extending centrally through it, and also has a hollow journal. Its journal fits in the frame I opposite the cylinder, and is secured there by means of a nut, j, screwed onto its end beyond the frame.

M designates a tube fitting at one end in the face of the bevel-wheel L, and having at the other end a flange which fits in the frame I adjacent to the end of the cylinder G. A cup-shaped washer, N, is interposed between the tube M and the frame I, and a washer, O, preferably made of lignum-vitæ, is interposed between this cup-shaped washer and the said tube.

P designates a cap fitting around the drill-spindle at the inner end of the cylinder G. It may be of cylindrical form, and has a flange which fits under the said end of the cylinder. A packing-ring, Q, of leather or other suitable material, is interposed between this cap and the flange of the tube M. This packing-ring bears on the drill-rod and obviates leakage around the same. The drill-spindle F passes through the tube M, the bevel-wheel L, and its hollow journal and extends beyond the same. It is locked to the tube M and the bevel-wheel

L by means of keys or splines L'. The drill-spindle will preferably consist of a metal pipe, as shown. To its outer end the drill-rod F' is secured by a screw-threaded coupling-piece, F². The inner end of the drill-spindle has affixed to it a tubular stem, F³, on which fits a cylindrical piece of metal forming the body of the piston H. Surrounding the stem F³, between the body-piece of the piston and a flange on said stem, are washers F⁴ F⁵, made of lignum-vitæ, having a metal washer, F⁶, fitted between them. Surrounding the stem F³ and fitting against the other end of the body-piece of the piston is a lignum-vitæ washer, F⁷. A cap-piece, F⁸, is screwed on the upper end of the stem and bears against the washer F⁷. Owing to this combination of parts the drill-spindle may be rotated without entailing the rotation of the piston, although it is directly connected with the piston. The cap-piece F⁸ is shown as perforated. When so made the motive agent will enter the drill-spindle and is conducted to the drill.

R designates a bevel-wheel, which gears into the bevel-wheel L, and is supported on a shaft which extends through one of the trunnions of the frame I. This bevel-wheel R, as here shown, is of larger diameter than the bevel-wheel L, and serves to drive the same to impart the necessary rotary motion to the drill-spindle. The shaft of the bevel-wheel R may be rotated by any suitable means.

The pipe K leads to a port, k, in the shell of a rotary valve, S. A pipe, K', leads from a port, k', in the shell of the said valve to near the inner end of the cylinder G. From a port, k², in the shell of the said valve a pipe, K², extends to the place where the waste or expended water or other motive agent is to be conveyed. A pipe, K³, leading from a port, k³, in one end of the shell of the valve, extends to the source of supply of the water or other motive agent. The plug of the valve S has a double port, l, which may establish communication between the port k and the port k², leading to the waste-pipe K². This port l may also, when the plug is properly turned, establish communication between the port k' and the port k², leading to the waste-pipe K². The same port, when the plug is otherwise turned, may establish communication between the ports k and k', so as to cut off communication between the cylinder G and the supply and waste pipes K³ K². The plug of the valve has also a port, l', which extends from its periphery to the central portion of one of its ends. When the plug of the valve is turned so that the port l will establish communication between the port k and the waste-port k² the port l' will establish communication between the port k' and the inlet-port k³, and when the plug is so turned that the port l will establish communication between the port k' and the waste-port k² the port l' will establish communication between the port k and the inlet-port k³. The

stem of the plug extends through the cap of the shell, and is provided with a hand-wheel, whereby it may be manipulated. The ports of the valve are so combined that the piston can never move forward with a sudden impulse in case the drill should work into a soft stratum, and thereby have the resistance offered to it suddenly reduced. This is accomplished by giving a lead to the inlet-port, so that a full head of the motive agent will be admitted while the exhaust or outlet port is but slightly open. The inlet-port l' and the outlet-port l are made of different width to attain this end.

What I claim as my invention, and desire to secure by Letters Patent, is—

1. In a drilling apparatus, the combination of a cylinder, a piston working therein, and a drill-spindle connected directly to the piston, so that it may rotate independently of the piston, and extending through the cylinder, substantially as specified.

2. The combination of the drill-spindle F, the cylinder G, the piston H, and the round stem F³, secured to the inner end of the drill-spindle and fitting in a round bearing in the body-piece of the said piston, whereby provision is afforded for the turning of the drill-spindle independently of said piston, substantially as specified.

3. The combination of the drill-spindle F, the cylinder G, the tube M, and the cap P and packing-ring Q, secured between the adjacent ends of said cylinder and tube, substantially as specified.

4. The combination of the cylinder G, the packing-ring Q, the cap P, the drill-spindle F, the tube M, and the lignum-vitæ washer O, substantially as specified.

5. In a drilling apparatus, the combination of a cylinder closed at one end, a piston fitting therein, and a drill-spindle connected directly to the piston, so as to be free to rotate independently thereof, substantially as specified.

6. In a drilling apparatus, the combination of a cylinder, a piston fitting therein, and a hollow drill-spindle connected to the piston and opening into said cylinder, substantially as specified.

7. In a drilling apparatus, the combination of a cylinder, a piston fitting therein, and a valve for controlling the same, provided with inlet-ports which are adapted to be opened in advance of the outlet-ports, substantially as specified.

8. The combination of the piston H, the drill-rod F, and the lignum-vitæ washers F⁶ F⁷, substantially as specified.

9. The combination of the cylinder G, piston H, pipes K K', valve S, containing in its shell ports k k' k² k³ and in its plug ports l l' and the pipes K² K³, substantially as specified.

J. B. WARING.
